(57) **CLAIM**

The ornamental design for a mobile phone holder, as shown and described.

DESCRIPTION

FIG. 1 is a front perspective view of a mobile phone holder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view of the mobile phone holder of FIG. 1, shown in an alternate position.

The broken lines in the drawings illustrate the portions of the mobile phone holder, which form no part of the claimed design.
